United States Patent Office

Des. 223,958
Patented June 20, 1972

223,958

GLIDESLOPE INDICATOR

Jon W. Hauser, St. Charles, Ill., assignor to General
Aviation Electronics, Inc., Indianapolis, Ind.

Filed Oct. 12, 1970, Ser. No. 25,445

Term of patent 14 years

Int. Cl. D10—99

U.S. Cl. D52—6

Fig.1.

Fig.2.

Fig.3.

Fig.4.

Fig.5.

FIG. 1 is a front elevational view of a glideslope indicator showing my new design;

FIG. 2 is a bottom plan view thereof;

FIG. 3 is a right end elevational view thereof;

FIG. 4 is a rear elevational view thereof; and

FIG. 5 is a left end elevational view thereof.

I claim:

The ornamental design for a glideslope indicator, as shown.
